UNITED STATES PATENT OFFICE

2,674,257

WATER FEED FOR BOILERS

Delroy McBride, Pocatello, Idaho

Application August 4, 1952, Serial No. 302,472

6 Claims. (Cl. 137—165)

1

This invention relates to an improved means for feeding water to a boiler, and is an improvement over the construction shown in my prior Patents No. 2,574,341, issued November 6, 1951, for Boiler Feed Trap, and No. 570,961, issued October 9, 1951, for Boiler Feed.

An object of this invention is to provide an improved and simplified means which is automatically operable for maintaining a predetermined water level in a boiler.

Another object of this invention is to provide a water feeding means for a boiler wherein the water which is to be discharged into the boiler is placed under boiler pressure so that the water can flow by gravity into the boiler.

A further object of this invention is to provide in a feeding means of this kind an improved steam valve and float actuated operating means therefor whereby the delivery tank will be filled to a predetermined degree before the steam valve is opened to admit steam to the delivery tank in order to equalize the pressure in the tank relative to the boiler so that the water can gravitatingly flow past a check valve into the boiler.

Another object of this invention is to provide a steam valve operating float in a delivery tank, releasable means for holding the float from movement in one direction, and a pilot float means associated with the releasable means for effecting release of the latter when the delivery tank is either full or substantially empty so that the steam valve float may move to either valve opening or closing position.

A further object of this invention is to provide means whereby the amount of water to be discharged into the boiler may be closely regulated.

With the above and other objects in view, my invention consists in the arrangement, combination and details of construction disclosed in the drawings and specification, and then more fully pointed out in the appended claims.

In the drawings—

Figure 1 is a fragmentary side elevation, partly in section, of a boiler feeding means constructed according to an embodiment of this invention,

Figure 2 is a sectional view taken on the line 2—2 of Figure 1,

Figure 3 is a sectional view taken on the line 3—3 of Figure 2,

Figure 4 is a sectional view similar to Figure 3, showing the floats in upper tank full position,

Figure 5 is a sectional view taken on the line 5—5 of Figure 3,

Figure 6 is a vertical section of the steam valve,

Figure 7 is a vertical section of the vent valve,

Figure 8 is a fragmentary outer side elevation of the adjusting means for the float locking levers,

Figure 9 is a sectional view taken on the line 9—9 of Figure 8,

Figure 10 is a fragmentary side elevation, partly in section, of the forward end of the main float,

Figure 11 is a fragmentary sectional view taken on the line 11—11 of Figure 5,

2

Figure 12 is a fragmentary sectional view taken on the line 12—12 of Figure 2,

Figure 13 is a fragmentary sectional view taken on the line 13—13 of Figure 2.

Referring to the drawings and first to Figure 1, the numeral 15 designates generally a conventional boiler with which the boiler feeder means to be hereinafter described is adapted to be associated. A water feeding tank generally designated as 16 is supported by suspension bars 17 above the boiler 15. The tank 16 comprises a main tank member 18 formed with an annular flange 19 and a small or end tank member 20 having a flange 21 which is secured by suitable fastening means 22 to the flange 19. The two tank members 18 and 20 form an elongated tank of suitable capacity which is adapted to gravitatingly feed water to the boiler 15.

The tank 16 has a combined inlet and outlet 23 with which a pipe 24 is connected and pipe 24 is connected to the upper portion of the boiler 15. A rearwardly closing check valve 25 is interposed in the pipe 24 and a cutoff valve 26 is interposed in pipe 24 between valve 25 and the boiler 15. A pre-heating water tank 27 is connected to pipe 24 by means of a pipe 30 and an outwardly closing check valve 31 is interposed in pipe 30.

A water supply pipe 32 is connected to the upper portion of the pre-heating tank 27 and is connected to a source of water supply under pressure. An electric valve 33 is interposed in pipe 32 and valve 33 is regulated as to the operation thereof by means of a float operated switch 34. The switch 34 is operated by means of a float 35 in a housing 36, and housing 36 is connected to a pipe 37 which is connected to the boiler 15. Switch 34 is connected by means of a conductor 38 to switch valve 33 and is connected by means of a conductor 39 to a source of current supply.

A supply conductor 40 is connected to the electric switch structure 33.

An auxiliary water supply tank 41 is disposed above tank 16 and is connected to pipe 24 by means of a pipe 42. A rearwardly closing check valve 43 is interposed in pipe 42 and a cutoff valve 44 is interposed in pipe 42 between valve 43 and tank 41. The tank 16 has mounted diametrically thereacross a shaft 45 which is mounted in U-shaped bearings 46 which are fixed to the inner side of the tank 16. A shaft locking pin 47 is extended across the upright arms of the bearings 46, as shown in Figure 13, so as to hold shaft 45 against upward movement and pin 47 is locked by means of a cotter pin 48.

A main float or valve operator generally designated as 49 is rockably mounted in the tank 16. The float 49 comprises a pair of elongated lever arms 50 and 51 which are formed with bearing sleeves 52 and 53 respectively at their inner ends and sleeves 52 and 53 are loosely mounted on shaft 45. The lever arms 50 and 51 have secured to the outer ends a closed buoyant body 54 which is fixed as by welding or the like between the outer ends of the arms 50 and 51. The main float

49 also includes rearwardly projecting short lever arms 55 and 56 extending rearwardly from the bearing sleeves 52 and 53 respectively, and counterbalancing weights 57 and 58 are fixed to the short lever arms 55 and 56 respectively.

A steam inlet valve generally designated as 59 is secured to the tank 16 and is connected by means of a pipe 60 to the boiler 15. A cutoff valve 61 is interposed in pipe 60. The steam inlet valve 59, as more clearly shown in Figure 6, is formed of a housing 62 which is threaded into a nipple 63 carried by the tank 16. The housing 62 is formed with a horizontally extending boss 64 with which pipe 60 is connected. A steam chamber 65 is formed in the upper portion of the housing 62, and a main steam valve 66 is disposed in chamber 65 and is gravitatingly and normally urged to engage a valve seat 67.

A main steam valve 66 is formed with a central bore or passage 68 and with a plurality of downwardly divergent passages 69. The valve 66 also includes a grooved guide member 70 which is slidable in a bore 71 formed by the seat 67. A pilot valve 72 normally engages a pilot valve seat 73 formed at the upper end of the bore 68 and is gravitatingly urged downwardly to closed position.

The pilot valve 72 includes an upwardly projecting valve stem 74 which is slidable in a guide or cage 75 which is threaded into the upper portion of a cylindrical sleeve or guide 76 fixed and projecting upwardly from the main valve plug 66. The guide sleeve 76 is formed with a plurality of openings 77 whereby steam will be permitted to enter the interior of the sleeve or guide member 76.

The housing 62 includes a lower guide member 78 and a downwardly projecting cage 79 formed with a guide 80 at the lower end thereof. A valve opening rod or stem 81 is slidable in the guides 80 and 78 and is formed with a reduced upper end 82 which is slidable in the bore 68 and is adapted at its upper end to engage the pilot valve 72. Upward movement of the stem or rod 81 will initially unseat the pilot valve 72 when the shoulder 83 which is formed at the lower end of the reduced stem or rod 82 engages the lower end of the grooved or ribbed guide 70 which projects from the main valve plug 66.

The steam valve 59 is adapted to be moved to open position when float 49 is in its uppermost position and this is accomplished by means of a vertically disposed rod 84 which is fixed at its lower end to a fitting 85 carried by a pin 86 which is extended through the arm 51. The rod 84 is slidable through a guide 87 which is welded or otherwise fixed to the inner side of the tank 16, and the upper end of rod 84 has a cup 88 fixed thereto and confronting the lower end of the rod 87. In the lowered position of the float 49 cup 88 is disposed in spaced relation to the lower end of rod or stem 81.

A vent valve generally designated as 89 is secured to the tank 16, extending downwardly through a boss or nipple 90 carried by the tank 16. The vent valve 89 comprises a housing 91 which is formed at its lower end with a reduced projection 92 having a vertical bore 93 which forms a guide for the valve stem, as will be herein-after described. An upwardly flared wall 94 is connected between the projection 92 and the housing 91 and is formed with a plurality of openings 95 which are disposed within the tank 16. The housing 91 is threaded onto the reduced lower end 96 of a plug 97, and the reduced

lower end 96 has threaded thereinto a valve seat 98.

The upper end of the plug 97 has a vent pipe 99 connected at one end thereto and the other end of the pipe 99 is connected to the upper end of a water heating coil 100 which extends vertically within the preheating tank 21. The lower end of the coil 100 has an exhaust pipe 101 connected therewith and pipe 101 may exhaust the steam to the atmosphere.

An upwardly closing conical vent valve plug 102 is disposed in housing 91 and is secured to the upper end of a valve stem or rod 103 which is slidable in a bore 93. The lower end of the valve stem 103 engages in a cup member 104 which is secured to the upper end of a vertical rod 105. The rod 105 is loosely secured at its lower end to the inner end of a valve closing lever 106 which is mounted on a downwardly projecting arm 107 fixed to the inner end of lever arm 50.

A pivot pin 108 projects from the arm 107 and lever 106 projects rearwardly from pivot 108 and has a weight 109 secured to the rear portion thereof whereby valve member 102 will be gravitatingly and normally urged upwardly to a closed position.

In order to provide a means whereby valve member 102 may be moved downwardly to an open position when float 49 is in its lower position, I have provided an upwardly projecting bar 110 which is secured at its lower end to a fitting 111 mounted on a pin 112 carried by the lever arm 50. The upper end of the bar 110 is formed with a right angularly disposed eye 113 which loosely engages about the valve stem 102 and is disposed on the upper side of a nut 114 which is threaded onto the stem 103. When float 49 rocks downwardly bar 110 will move therewith and will draw valve plug 102 downwardly to an open position against the urging of weighted lever 106.

The main float 49 is adapted to be locked in either an upper or lower position by means of a pair of oppositely disposed locking levers 115 and 116. The lever 115 is pivotally mounted on a shaft or pin 117 carried by a crank arm 118. The crank arm 118 is disposed in a laterally offset housing 119 which is formed on one side of the tank 16. A crankshaft 120 is secured to crank arm 118 and projects through a bearing boss 121 carried by the outer wall 122 of offset housing 119. A lever 123 is fixed to shaft 120 on the outer side of housing 119 and one end of a lever adjusting bolt 124 is rotatably mounted in arm 123. Bolt 124 is threaded through a nut 125 which projects from the outer wall 122.

Lever 115 is constantly urged downwardly to a locking position with the lower end thereof engaging a roller or wheel 126 mounted on a pin 127 carried by the arm 51 by means of an offset weight 128. Locking lever 116 is rockably mounted on a shaft or pin 129 which is secured to a crank arm 130 and crank arm 130 extends right angularly from a crankshaft 131. Shaft 131 projects through a bushing or boss 132 carried by the outer wall 122 of housing 119, and a crankshaft adjusting lever 133 is fixed to the outer end of shaft 131. A shaft adjusting screw 134 is rotatably secured to the crank 133 and is threaded through a nut 135 which is carried by the wall 122. Lever 116 has projecting therefrom a weight 136 whereby lever 116 will be constantly urged to swing upwardly for engagement with the roller 126.

In order to provide a means whereby the levers 115 and 116 may be alternately moved to a re-

leased position to thereby permit upward or downward movement of float 49, I have provided a pilot float 137 which is carried by an arm 138, with a buoyant body 139 secured to arm 138 and positioned between the arms 50 and 51. The inner end of arm 138 is secured to a sleeve 140 which is loosely mounted on shaft 45 between the levers 50 and 51. A rearwardly projecting short lever arm 142 projects from the bearing sleeve 140 and has a counterbalancing weight 143 secured to the rear end thereof. One end of sleeve 140 has fixed thereto a pair of oppositely extending levers 144 and 145, the purpose for which will be hereinafter described.

A pair of elongated cam carrying rods 146 and 147 are disposed in substantially parallel relation to each other, and to the lever arm 51. The outer ends of the rods 146 and 147 are slideable through bushings 148 and 149 respectively which are secured to the buoyant member 54. The inner or rear ends of the rods 146 and 147 are adjustably threaded into sleeves 150 and 151 which are pivotally secured at their inner or rear ends to the lever arms 144 and 145 respectively.

Rod 148 has a lock releasing cam 152 secured thereto which upon rearward movement of rod 146 is adapted to engage locking lever 115. Rod 147 has a lever releasing cam 153 fixed thereto which upon rearward movement of rod 147 is adapted to engage lever 116.

In the use and operation of this device, the tank 16 is disposed in an elevated position above the boiler 15 and preferably tank 41 is also elevated above tank 16. Initially valves 26 and 61 are open so that when the water level in boiler 15 reaches a predetermined low, float 35 will close switch 34 and energize electric valve 33 so that this valve will be moved to an open position. Assuming that main float 49 is initially in its lowered position, with tank 16 empty, at which time valve 33 was previously closed, switch 34 will be moved by float 35 to a circuit closing position so as to open valve 33. At this time water will flow from preheating tank 27 past check valve 31 into tank 16. With float 49 in its lower tank empty position, vent valve 89 will be held in an open position and main float 49 will be locked in its lower position by means of upper locking lever 115. As tank 16 fills with water, pilot float 137 will rise and when pilot float 137 is substantially at its uppermost position, cam 152 will contact with lever 115 and swing lever 115 from locking contact with roller 126. Main float 49 will then rapidly swing upwardly to its uppermost position and at this time lever 115 will swing rearwardly as shown in Figure 4. Lower locking lever 116 will, under the action of weight 136, swing upwardly to the position shown in Figure 4, with the upper end of lever 116 in locking engagement with roller 126. When float 49 swings rapidly upwardly under the buoyancy of buoyant member 54, vent valve plug 102 will be moved upwardly to a closed position by means of the weighted lever 106 and at the same time cup 89 carried by rod 84 will push valve operating rod 81 upwardly to initially open pilot valve 73 and subsequently open main steam valve 66. When steam valve 66 is in an open position, being held in such position by the main float 49, steam will enter tank 16 above the water level so that the steam pressure in tank 16 will be equal to the steam pressure in boiler 15. With the steam pressure equal in tank 16 and boiler 15, the weight of water in tank 16 will open check valve

25 and tank 16 will thereby empty into boiler 15. As the steam flows through steam valve 59, the steam entering tank 16 will contact with a baffle 154 which is secured to the upper portion 5 of tank 16 so that the steam will be distributed within the empty space in tank 16 above the upper water level.

As the water empties from tank 16, pilot member 137 will float downwardly with the dropping 10 of the water and at this time lever arm 145 will be rocked rearwardly so that cam 153 will in substantially the lower position of pilot float 137 contact locking lever 116 so as to thereby unseat or release lever 116 from roller 126. Main 15 float 49 upon release from lever 116 will rapidly swing downwardly and a bumper 155 is preferably secured to the inside of the tank 16 for engagement with weight 136. As main float 49 reaches the end of its downward movement, steam 20 valve 59 will be released from valve operating rod 84 so that valve plug 86 and pilot 72 will gravitantly move downwardly to a closed position. At the same time that steam valve 59 is moving to a closed position, vent valve 102 is 25 drawn to an open position by downward movement of bar 113 with eye 113 contacting nut 114. Adjustment of the pivot members or shafts 117 and 129 by the adjusting bolts 124 and 134 respectively will regulate the uppermost and low- 30 ermost positions of the main float 49. The boiler feeding means hereinbefore described will go through its filling and emptying cycles until the boiler 15 has the water level thereof raised to a point where float 35 will move switch 34 to a 35 circuit breaking position. With switch 34 in a circuit breaking position, the water feeding means will be inactive and will remain inactive until the water level in boiler 15 again reaches a predetermined low point.

40 I do not mean to confine myself to the exact details of construction herein disclosed, but claim all variations falling within the purview of the appended claims.

What I claim is:

45 1. A water feeding means for a boiler comprising a tank having a combined inlet and outlet, means connecting said combined inlet and outlet with a source of water supply, means connecting said combined inlet and outlet with the boiler, 50 a steam valve carried by said tank, a valve operating float in said tank, a float supporting lever rockably disposed in said tank, an operative connection between said lever and said valve for moving the latter to open position when said 55 float rises to a predetermined degree, a releasing float in said tank, a rock lever fixed to said releasing float, a pair of oppositely disposed float locking levers in said tank engageable with said first-named lever for alternately locking the latter in an upper or a lower position, a pair of lever releasing members carried by said first-named float and lever, means operable by movement thereof said releasing float engageable with said 60 releasing members for moving the latter to effect release of said locking levers when said tank is substantially filled or emptied.

65 2. A water feeding means for a boiler comprising a tank having a combined inlet and outlet, means connecting said combined inlet and outlet with a source of water supply, means connecting said combined inlet and outlet with the boiler, a steam valve carried by said tank, a valve operating float in said tank, a float supporting lever rockably disposed in said tank, an opera-

tive connection between said lever and said valve for moving the latter to open position when said float rises to a predetermined degree, a releasing float in said tank, a rock lever fixed to said releasing float a pair of oppositely disposed float locking levers in said tank engageable with said first-named lever for alternately locking the latter in an upper or a lower position, a pair of lever releasing members carried by said first-named float and lever, means operable by said releasing float engageable with said releasing members for moving the latter to effect release of said locking levers when said tank is substantially filled or emptied, a vent valve, weight operated means for normally urging said vent valve to closed position, and means connected between said first-named float and said vent valve for holding said vent valve in open position when said first-named float is in lowered position.

3. A water feeding means for boilers comprising a tank having a combined inlet and outlet, means connecting said combined inlet and outlet to a source of water supply, means connecting said combined inlet and outlet with the boiler, a steam valve carried by said tank connected with the boiler, a vent valve carried by said tank, a buoyant steam valve operator, means connecting said operator with said steam valve for moving the latter to open position when said tank is full, means normally urging said vent valve to closed position, means connecting said operator with said vent valve for moving said vent valve to open position at the time said steam valve is also moved to closed position, a pair of opposed operator locking levers, alternately operable to lock said operator in an upper or a lower position, pivot means for said locking levers, swingable supporting means for said pivot means, means engageable exteriorly of said tank for adjusting said supporting means to thereby vary the movement of said operator, lever releasing means carried by said operator, and a lever releasing float cooperating with said releasing means for actuating the latter to release said operator when said tank is full or empty.

4. A water feeding means for boilers comprising a tank having a combined inlet and outlet, means connecting said combined inlet and outlet to a source of water supply, means connecting said combined inlet and outlet with the boiler, a steam valve carried by said tank connected with the boiler and normally disposed in closed position, a vent valve carried by said tank, a shaft disposed diametrically across said tank, bearings in said tank for said shaft, a main float, a rock lever fixed to said main float and rockably carried by said shaft, a pilot float, a rock lever fixed to said pilot float and rockably carried by said shaft, means carried by said first-named lever engaging said steam valve for moving the latter to open position when the tank is full, means carried by said first-named lever moving said vent to normal closed position when the tank is full, said latter means also effecting opening of said vent valve when the tank is empty, a pair of opposed gravity operated locking levers rockably carried by said tank and alternately engageable with said first-named lever for locking the latter in either an upper or a lower position, and means operable by said second named lever engageable with said pair of levers for releasing the latter at the time the tank is either full or empty whereby said main float will move rapidly from a lower to an upper position, or from an upper to a lower position.

5. A water feeding means for boilers comprising a tank having a combined inlet and outlet, means connecting said combined inlet and outlet to a source of water supply, means connecting said combined inlet and outlet with the boiler, a steam valve carried by said tank connected with the boiler and normally disposed in closed position, a vent valve carried by said tank, a shaft disposed diametrically across said tank, bearings in said tank for said shaft, a main float, a rock lever fixed to said main float and rockably carried by said shaft, a pilot float, a rock lever fixed to said pilot float and rockably carried by said shaft, means carried by said first-named lever engaging said steam valve for moving the latter to open position when the tank is full, means carried by said first-named lever for moving said vent to normal closed position when the tank is full, said latter means also effecting opening of said vent valve when the tank is empty, a pair of opposed gravity operated locking levers rockably carried by said tank and alternately engageable with said first-named lever for locking the latter in either an upper or a lower position, means substantially balancing said main and pilot floats, and means operable by said second named lever alternately engageable with said pair of levers for releasing the latter at the time the tank is either full or empty whereby said main float will move rapidly from a lower to an upper position, or from an upper to a lower position.

6. A water feeding means for boilers comprising a tank having a combined inlet and outlet, means connecting said combined inlet and outlet to a source of water supply, means connecting said combined inlet and outlet with the boiler, a steam valve carried by said tank connected with the boiler and normally disposed in closed position, a vent valve carried by said tank, a shaft disposed diametrically across said tank, bearings in said tank for said shaft, a main float, a rock lever fixed to said main float, rockably carried by said shaft, a pilot float, a rock lever fixed to said pilot float and rockably carried by said shaft, means carried by said first-named lever engaging said steam valve for moving the latter to open position, when the tank is full, means carried by said first-named lever for moving said vent to normal closed position when the tank is full, gravity operated means carried by said shaft effecting opening of said vent valve when the tank is empty, a pair of opposed gravity operated locking levers rockably carried by said tank and alternately engageable with said first-named lever for locking the latter in either an upper or a lower position, means for adjusting said pair of levers to thereby vary the locking positions of said first-named lever, and means operable by said second named lever engageable with said pair of levers for alternately releasing the latter at the time the tank is either full or empty whereby said main float will move rapidly from a lower to an upper position, or from an upper to a lower position.
